(57) **CLAIM**

The ornamental design for a feeder and waterer, as shown and described.

DESCRIPTION

FIG. 1 is a front view of the feeder and waterer;
 FIG. 2 is a right side view of the feeder and waterer;
 FIG. 3 is a top view of the feeder and waterer;
 FIG. 4 is a left side view of the feeder and waterer;
 FIG. 5 is a front upper perspective view of the feeder and waterer;
 FIG. 6 is a rear upper perspective view of the feeder and waterer; and,
 FIG. 7 is a back view of the feeder and waterer.
